UNITED STATES PATENT OFFICE.

EDWIN J. HOUSTON AND ELIHU THOMSON, OF PHILADELPHIA, PENNSYLVANIA, ASSIGNORS TO THE THOMSON-HOUSTON ELECTRIC COMPANY.

DYNAMO-ELECTRIC MACHINE.

SPECIFICATION forming part of Letters Patent No. 296,569, dated April 8, 1884.

Application filed November 30, 1878.

To all whom it may concern:

Be it known that we, EDWIN J. HOUSTON and ELIHU THOMSON, both of the city and county of Philadelphia, State of Pennsylvania, have 5 invented a certain novel and useful Dynamo-Electric Machine, of which the following is a description.

Our invention consists in the combination, with two field-of-force poles, respectively of 10 north and south polarity, of a plurality—that is, a greater number—of armature coils or bobbins, so that the reversal of current shall take place successively and not simultaneously in all of said bobbins, one-half of the terminals 15 of said coils or bobbins being connected together or to a common conductor, while the remaining ends are separately connected to the separate segments or plates of a commutator, to which are applied the positive and 20 negative collectors of the machine.

Figure 1 shows in end and side view the commutator and a common collecting ring or disk for electrically uniting one-half of the terminals. Fig. 2 illustrates the relation of the 25 armature-coil terminals to the field-of-force poles, and shows the manner in which the parts are connected. Fig. 3 shows the manner of constructing a commutator-brush to allow for wear.

30 Fig. 1 shows an armature adapted to eight separate coils or bobbins, A B C D E F G H, being the separate commutator plates or segments suitably mounted upon the shaft X. R indicates a metallic ring or disk, also mounted 35 upon the shaft, to which disk one end of each armature-coil of the set or series used in connection with the commutator is connected. The two ends of the various armature-coils are indicated by the letters a' b' c', &c., the same 40 ends—for instance, the outer ends of the coils or bobbins—being distinguished by the prime-mark. Thus, supposing that there are eight coils or bobbins used with the commutator, there will be sixteen terminals, two, as a' or 45 b', &c., from each coil, as indicated in Fig. 2. When two field-magnet poles act to induce currents in the armature-coils, as there indicated, said currents are induced successively, as one coil after another passes the 50 poles, and the armature-coil terminals will reverse their polarity at each semi-revolution.

If the machine be so constructed that the coils reverse their polarity on the line x x, all the terminals, as a b h, above that line that are connected to the commutator-plates will be of one 55 polarity, and all similar terminals, as d e f, below that line that are connected to the commutator-plates will be of the opposite polarity; but as there are more armature coils or bobbins than field-of-force poles, the reversal does not take place simultaneously in all. The terminals a' b' h' will, if the armature is 60 symmetrically made up, be simultaneously of the opposite in polarity to the terminals a b h, and similarly the terminals d' e' f' will be 65 opposite to d e f. Taking, then, all the terminals of the four bobbins on the same side of the line X X that are the same moment positive, and all those terminals of the four bobbins on the opposite side that are at the same 70 time negative, we connect them together by joining them to the common ring or plate, R. The remaining terminals are joined *seriatim* and separately to the commutator-plates, following the same order as that belonging to the 75 coils or bobbins in passing through the magnetic field.

In Fig. 2, Z indicates in outline the armature structure upon which the bobbins or coils are wound or supported in any of the usual 80 ways.

The collecting-brushes P N consist of pairs of springs, 1 1, 2 2, 3 3, the two springs of each pair bearing on diametrically-opposite plates, while the three upon the same side of commutator are joined together to make a compound brush, which, as will be readily seen, collects the current simultaneously from those coil-terminals which are for the time being of the same polarity. If desired, four pairs of springs 85 might be used, so as to include all the eight coils. By joining the brushes P N through a working-resistance, R', the currents from the bobbins which are at the same time of opposite polarity are utilized for tension, while at 90 the same time, owing to the fact that the reversals do not take place in all the bobbins at once, but only in succession, the current will be very uniform.

We do not restrict ourselves to any particular number of bobbins or coils, as it is obvious that the same results and the same prin- 100

5 ciple of operation might be attained by using a larger or a smaller number than the number herein shown. If a smaller number were used, however, there would be theoretically less uniformity in current, although the same advantages in kind would result from the plurality of bobbins as compared with the number of field-poles to which said bobbins are simultaneously exposed.

10 We prefer to make the collecting springs or brushes for the machine in the following manner, so that they may be fed forward to compensate for wear:

15 In Fig. 3, P represents the support for a commutator brush or spring, M, on which post is supported a lever or spring, L, a free end of which rests upon M in such manner that by means of a screw, T, the pressure of M upon the commutator-cylinder may be increased or diminished. A strip of flexible metal, as copper, S, is placed under the spring M, one extremity of the same resting in contact with the cylinder. As this extremity wears away, the strip S is pushed forward, 20 while the spring M is protected from wear. 25 W shows a coiled length of the strip S.

We apply our invention to any form of dynamo-electric machine having on its armature one or more series of coils or one or more 30 series of terminals taken from the same coil, said terminals being of various polarity at the same moment, as described.

What we claim as our invention is—

1. In a dynamo-electric machine, the combination, with two field-poles of opposite polarity, of a plurality of armature-bobbins or coils simultaneously exposed to the inducing action of said poles, half of the terminals of

which bobbins are joined together or to a common conductor, while the remaining terminals 40 are connected to separate segments of a commutator.

2. The combination, with two diametrically-opposite inducing-poles in a dynamo-electric machine, of a plurality of armature coils or 45 bobbins, the similar ends of which coils are joined separately to the separate plates of a commutator, while their opposite ends are united in a common electrical joint or connection, and two collecting-brushes or sets of 50 brushes applied to said commutator, and forming, respectively, the positive and the negative collector of the machine.

3. The combination, in a dynamo-electric machine, of two diametrically-opposite field-of-force poles, a plurality of armature-coil terminals joined *seriatim* to the plates of a commutator, a common joint or connection for the opposite terminals of the coils, and a positive and negative collector applied to 60 said commutator, and each arranged to collect the current in multiple arc from those terminals which are for the time being on the same side of the shaft and are of the same polarity.

4. In a commutator for a dynamo-electric machine, the combination of an adjustable plate or spring, M, and a flexible band or strip, S, of conducting material, substantially as described.

EDWIN J. HOUSTON.
ELIHU THOMSON.
